CAN REGISTERING MEANS

George A. Bardet and George V. Bardet, Berkeley,
Calif., assignors to M. J. B. Company, a corpora-
tion of Delaware

Application May 17, 1935, Serial No. 22,042

5 Claims. (Cl. 216—58)

This invention relates to can registering means, and it has reference to registering means to be used in connection with can labeling machines, although not limited to this particular use.

5 More particularly, the present invention applies to machines of that type designed for applying paper strip labels to cylindrical cans, and wherein the cans to be labeled are rolled in succession along a receiving guideway, passing across 10 a supply stack of labels to cause each can, in passing, to pick up the upper label from the stack and wrap it about the can incident to its continued travel along the guideway.

15 The principal object of the present invention is to provide a can registering means whereby a designated part of a can may be accurately positioned with reference to its location in the guideway or with reference to some other object or device used in connection with the can.

20 More specifically stated, the object of the invention is to provide can registering means that is applicable to the commonly used types of labeling machines as above described, whereby each can, in its promiscuous delivery into the machine, will momentarily be stopped in the guideway prior to reaching the label stack, and there 25 will be mechanically positioned to insure that a designated portion of the can will, upon subsequent travel of the can across the label stack, come accurately into registration with a designated portion of the label.

30 Heretofore, it has not been customary, or at least it has not been considered desirable, to apply paper strip labels to tearing strip cans. 35 It has been the general practice for this type of can, to lithograph the body blanks prior to making them into bodies, and to thus eliminate the necessity or desirability of applying paper labels. Generally when paper labels have been applied to tearing strip cans, they have been so positioned that they did not overlap the tearing strip since it is quite apparent that, should the tearing strip tongue be covered up by the label, it would be required, for an application of a key thereto, that the location of the tongue first be determined, then a part of the label torn away to expose the tongue. Should the label be made sufficiently short that it did not extend over the tearing strip, the uncovered portion of the can body 40 should be lithographed; otherwise, it presents an unattractive appearance. To our knowledge, no attempt has been made heretofore to cover the entire body wall of a can with a label having a recess through which the tearing strip tongue is exposed to view.

The present invention contemplates the application of paper strip labels to tearing strip cans which will cover the can between its ends and which will extend across the tearing strip, and which are provided with notches or "cut outs" 5 at one edge for exposing the tearing strip tongue of each can to view. Therefore, the object of the invention, broadly stated, is to provide an attachment means for standard, or other types of labeling machines, whereby each can, after 10 entering a machine, will be accurately registered for exposing its tearing strip tongue within the notch of the label which is applied thereto.

More specifically stated, the present invention resides in the provision of an attachment means 15 for labeling machines, including a stop member in the receiving guideway by which each can is momentarily stopped in its forward travel, while rotation thereof is continued, and also including a switch lever positioned to engage with any natural or artificial projection on the body of the 20 rotated can, thereby to actuate the switch to close an electric circuit through means whereby the stopped can is instantly released for continued travel, with the tearing strip tongue accurately located for registration within the notch 25 of the label which the can picks up in its passage over the label stack.

Other objects of the invention reside in the details of construction, in the combination of 30 parts, and in the mode of operation, whereby the various objects of the invention are attained.

In accomplishing these, and other objects, we have provided the improved details of construction, the preferred forms of which are illustrated 35 in the accompanying drawings wherein—

Fig. 1 is a plan, or top, view of a labeling machine to which the present invention has been applied.

Fig. 2 is a longitudinal section in a vertical 40 plane of the machine as seen on the line 2—2 in Fig. 1.

Fig. 3 is an enlarged plan of the attachment device.

Fig. 4 is a vertical section of the mechanism 45 as seen on line 4—4 in Fig. 3.

Fig. 5 is a similar sectional view, illustrating the position of the can spacing and stop mechanism in normal position and showing the switch lever in circuit closing position.

Fig. 6 is another similar sectional view, illustrating the release operation of the can spacing stop member.

Fig. 7 is a perspective view, illustrating the lo- 55

cation of a tearing strip tongue within the notch of a label applied to a can body.

Referring more in detail to the drawings—

1 designates a horizontal runway along which the cylindrical cans 2 are caused to be rolled by contact with the lower run of a can delivery belt 3, operating parallel with the guideway about belt wheels 4 and 5; the wheel 4 being supported on a cross shaft 6 that is revoluble in supporting bearings 7—7 fixed to the guideway, and the wheel 5 being fixed on a cross shaft 9 that is supported at its ends in bearings 10—10 also fixed to the guideway.

The belt 3 and the wheel 5 are located centrally above the guideway, as observed by reference to Fig. 1, and at opposite sides of the wheel 5 are paired belt wheels 11—11, fixed on the shaft 9, and about which belts 12—12 extend; the latter belts having their lower runs parallel with the runway and adapted to continue the advancement of the cans along the runway as delivered thereto by the belt 3, and to advance them under positive control across the glue applying rolls, and the label stack, which will now be described.

25 As observed in Fig. 2, a glue pot 13 is supported directly beneath the guideway 1. This pot contains revolvably driven glue applying rollers 14 fixed on a cross shaft 15 that is rotated in any suitable manner such as by means of the belt 16 operating over pulleys 17 and 18 fixed, respectively, on shafts 9 and a shaft 19 which, in turn, is operatively connected by gearing 19a, with shaft 15, as seen in Fig. 1. The glue applying rollers 14 are so disposed that the cans delivered by the belts 12 along the guideway will contact therewith for an application of glue to the can body at intervals along a line from end to end.

Located at a specified distance from the glue rolls 14 and below the runway is a support 20 upon which a stack of paper strip labels 21 is placed. Each label in this instance has a notch or recess 21a at one edge within which the tearing strip tongue of the can to which the label is applied, will register. The labels are disposed lengthwise of the runway, and the stack is fed upwardly as the labels are used by suitable means, which is not herein illustrated. The upward travel of the stack is limited by means of a narrow in-turned flange 24 overlying the stack at its forward edge and a transverse belt 25 which overlaps it at its opposite edge. This latter belt is continuous and is extended about belt wheels 26 and 27; the latter of which is located in a paste container 28 from which a suitable paste is transferred to the belt for subsequent application to the ends of the labels with which it contacts.

It is to be understood that in the present arrangement, the cans, in passing over the glue rollers 14, have a small amount of glue applied thereto, and that the label stack is so spaced from the rollers that after the can has made at least one complete revolution in its travel along the guideway, the glued areas of the can come into contact with the forward end of the upper label 65 of the stack, and the end of the label adheres thereto, then as the can continues to roll along the guideway, the label is thereby caused to be wrapped about the can, and the opposite end of the label to which paste has been applied by belt 70 25 is caused to overlap and adhere to the first attached end of the label, thus securing it about the can body.

Since the present invention contemplates the labeling of tearing strip cans by means of labels 75 which have an edge notch formed therein for ex-

posing the tearing strip tongues, the position of the can in its delivery across the label stack must therefore be accurately determined prior to the can's reaching the label. In carrying out the objects of the invention, a mechanism has been provided for temporarily stopping each of the cans as it is rolled along the guideway by the delivery belt 8 but permitting a continued rotation of the can under action of the belt to bring the tongue to a definite position, following which, the can is released for continued travel along the guideway.

This tongue registering means is illustrated particularly in Figs. 3 to 6 wherein 30 designates a cross rod normally supported in the path of the cans as delivered under control of the belt 3. This cross rod is to successively stop the forward travel of the cans, and it is supported at its opposite ends by arms 31—31, which, in turn, are fixed on a cross shaft 32 located transversely of, and just beneath the guideway on which the cans travel, 20 and is revoluble at its ends in spaced supporting plates mounted on the frame structure.

When a can is stopped in its advancement by cross rod 30, it continues to revolve by reason of its contact with belt 3, and while it revolves, it is supported at its opposite ends upon rollers 34—34 revoluble on parallel cross rods 35—35 that extend between the plates 33—33. A roller 36 directly overlies the belt 3 above the stopped can and holds the latter seated on the rollers 30 while it revolves.

The means for supporting the cross rod 30 in position to arrest a can during its registration period comprises a lever arm 38 that is fixed on the shaft 32, and which extends downwardly into 35 abutment with the end of a stop lever 39; the latter being disposed horizontally and pivotally mounted at its end, opposite that which engages the arm 38, on a cross shaft 40, and is yieldingly held in a raised, functional position by a spring 41, which is wound on the shaft adjacent the arm and has its ends fixed, respectively, to the arm and shaft, as seen in Fig. 3. A coiled spring 43 is attached at one end to the lower end of a pin 44 fixed in the shaft 32 at its other end to a pin 45 fixed in a plate 33, in such manner as to draw the stop rod 30 back to its raised position after each time it is depressed, as illustrated in dotted lines in Fig. 5, by the passage of a can thereover.

Release of the stop lever 39 is incident to the 50 energization of a solenoid 46 supported below the free end of the lever and adapted, when energized, to draw that end of the stop lever 39 downwardly against the core of the solenoid, as in Fig. 5, thus to free the arm 38 and permit the stop bar 55 to be depressed by the action of the can for the passing of the can thereover.

The solenoid 46 is connected electrically with a source of electricity 47 by circuit wires 48 at one side and a wire 49 and control switch at the other side. The control switch comprises two spring metal contact strips 52 and 53, with ends mounted on an insulating block 54, and connected, respectively, to the one pole of the solenoid and to the wire 49, with their other ends 65 normally disengaged but adapted to be pressed together to close the circuit through the solenoid.

Rotation of the can is for the purpose of bringing a certain part thereof into a definite position relative to some other mechanism or to its position on the guideway. Then the can is released for advancement.

In order that the solenoid may be energized at exactly the proper time for release of the can, a switch lever 55 is pivotally mounted between the 75

rollers 34—34 supporting one end of the can. This lever has a short end portion 55a disposed in a position terminating close to the can body wall, and it also has a relatively long opposite end portion 55b terminating adjacent the contact 52. The arrangement of the lever is such that, incident to rotation of the can, the seam bulge, designated at 58, on the double seam of the can body, will contact the lever end 55a, thereby to actuate the lever, as in Fig. 5, to a position that its lower end presses the contact 52 against the contact 53, thereby to momentarily close the solenoid circuit to energize the solenoid to magnetically draw the stop lever 39 downwardly to release the arm 38 and incidentally permit the advancement of the registered can along the guideway. Coincident with the release of the can, the solenoid circuit is opened and the lever 39 is moved back to raised position by spring 41. Then, as the can passes over the stop bar 30, the latter will be swung back to raised position by spring 43 and the arm 38 will again lock back of the lever 39.

During the registration period of any can stopped by the cross bar 30, the next oncoming can is held back in the guideway at a distance spaced from the can being registered, by means of a cross rod 60 disposed transversely of the path of delivery and supported at its ends by arms 61—61 fixed on a cross shaft 62 that is revolvably mounted at its ends in the frames 33—33. The shaft 62 has a depending arm 63 fixed thereto, and a coiled spring 64 is attached to the arm and to a stud 65 in a manner to raise the cross rod 60 back to its functional position in the runway after a can has been advanced thereover. The depending arm 63 also is adapted to lock within a notch 66 at one end of a latch lever 67 that is pivotally mounted at its other end on the cross shaft 40. This latter lever is adapted to be held in raised position against a limiting stop by a coil spring 68 wound on shaft 40 and attached at its opposite ends to the arm and shaft as shown in Fig. 3.

When a registered can is released and has passed over the cross bar 30, it is then utilized as the means of effecting the release of the cross bar 60 for the advancement of another can to the registering position. The release action of the stop, or latch lever, 67 is effected by a solenoid 70, located beneath the free end of this lever. Energization of the solenoid 70 operates to draw the latch lever to releasing position. The solenoid is connected in a circuit with the source of electricity 47 by means of wires 71 and 72, and there is a switch interposed in the wire 72. This switch comprises a pair of spring strip contacts 73 and 74 with ends mounted on an insulating block 75, fixed in the frame structure. Normally, the free ends of the contacts are in spaced relationship, thereby to retain the circuit open. However, as the released can advances along the runway beyond the stop lever 30, it passes over a switch lever 78 which is pivotally supported by a cross rod 79 with one end disposed in a position to be depressed by the passing can, and its other end in position to engage and move the contact 73 against the contact 74, thereby to momentarily energize the solenoid to effect the release of the latch lever 67. The momentary release of the latch lever permits the can then held by the stop bar 60 to be advanced to the registering position, but the next oncoming can will be checked by the cross rod 60 which is swung back into functional position by spring 64.

Each released, registered can passes across the

glue applying rolls 14, and has spots of glue applied thereto from end to end. The location of the rollers for applying the glue is definite in spacing from the label stack so that, when the can reaches the label stack, the glue bearing portion of the can wall will engage with the forward end of the label, which will adhere thereto and effect the wrapping of the label about the can incident to its continued travel along the guideway, as will be well understood by persons familiar with this art. Also, the position of registration of the can is such that the tearing strip tongue will be brought accurately into registration with the label notch.

It is readily apparent that with this above described mechanism, each can received at the registering position and stopped by the cross bar 30 upon the supporting rolls 34, will be rotated by reason of its contact with belt 3. Any normal, or artificial, projection formed on the can body, or on the double seam, may be utilized as a means of actuating the switch lever to effect the release of the can. For instance, the tongue of the can might be employed in the same manner as the bulge formed in the overlap in the seam as herein employed, and while we have illustrated the stop mechanism as being applied to a can labeling machine, it is to be understood that it might also be used in connection with any attaching devices or any other machine arranged for operation on a can and requiring that the can be received in the machine in a definite relationship.

It is to be understood that various details of construction might be altered without departing from the spirit of the invention. Therefore, it is not intended that the claims shall be restricted to details of construction, but that they shall be given an interpretation commensurate with the scope of the invention disclosed.

Having thus described our invention, what we claim as new therein, and desire to secure by Letters Patent is:

1. In a machine of the character described, a can guideway along which cans are caused to advance, a releasable stop arranged to successively stop the cans in their advancement, each for a period of axial rotation, latch means for supporting the stop in functional position, and a release mechanism for the said latch means including a solenoid, an electric circuit therefor, and a circuit control member disposed in position to be actuated by a part of the rotating can offset from its normal curvature, to close the circuit to energize the solenoid and thereby effect release of the latch, and a second stop member adapted to withhold oncoming cans spaced from the can being rotated, and a release for said second stop disposed in position to be actuated by a registered can in its travel along the guideway after release by the first stop.

2. In a machine of the character described, a can guideway along which cans are caused to advance, a releasable stop arranged to successively stop the cans in their advancement, each for a period of axial rotation, latch means for supporting the stop in functional position, and a release mechanism for the said latch means including a solenoid, an electric circuit therefor, and a circuit control member disposed in position to be actuated by a part of the rotating can offset from its normal curvature, to close the circuit to energize the solenoid and thereby effect release of the latch, and a second stop member operating in timing with the first mentioned stop.

to withhold oncoming cans in spaced relation to the can being rotated, and a release means for the second stop operating under control of cans released from the first stop.

5. In a machine of the character described, a can guideway, driven means whereby cylindrical cans, due to rolling contact therewith, are caused to be advanced along the guideway, a spacing stop and a registering stop disposed on the guideway whereby two adjacent cans are held in spaced relation for a period of axial rotation and registration of the can farthest advanced, a latch member for each of said stops, a means for each latch adapted to be electrically energized to actuate its latch member to released position, an electric circuit for each means, a switch for the circuit corresponding to the registering stop, having a closing member disposed for actuation by a part of the can that is stopped for axial rotation, and a switch for the circuit of the spacing stop having a closing member disposed to be actuated by a can released from the registering stop.
4. In a machine of the character described, a can guideway, a can registering stop associated with the guideway, means whereby cans are caused to be advanced along the guideway and

against said stop and axially rotated while stopped thereby, a releasable latch member normally positioned for holding the registering stop in functional position, a release mechanism for said latch member including a control element disposed in position to be functionally actuated by a part of the stopped can offset from its normal curvature and which is caused to actuate said control element incident to the axial rotation of the stopped can, another releasable stop member associated with the guideway for stopping a next succeeding can in the guideway during the period of rotation of a can being registered, and a trip for controlling the releasing of said second stop member positioned to be functionally actuated by the advancement of a registered can along the guideway.

5. A device as in claim 4 wherein each of the stop members has an individual releasing solenoid, an electric circuit therefor, and a control switch for the circuit and wherein the control switch for the circuit of the first mentioned stop is actuated by the said control element, and the control switch of the second stop is actuated by said trip.
